UNITED STATES PATENT OFFICE.

JOHN R. BROWN, OF MANSFIELD, OHIO, ASSIGNEE TO THE OHIO BRASS COMPANY, OF MANSFIELD, OHIO, A CORPORATION OF NEW JERSEY.

RAIL-BOND.

1,263,463.

Specification of Letters Patent. Patented Jan. 15, 1918.

Application filed September 27, 1916. Serial No. 120,411.

To all whom it may concern:

Be it known that I, John R. Brown, a citizen of the United States, residing at Mansfield, in the county of Richland and State of Ohio, have invented certain new and useful Improvements in Rail-Bonds, of which the following is a specification.

My invention relates to that class of devices known as rail bonds the purpose of which is to join the adjacent ends of rails together electrically.

My invention has as its object a device which is easy of manufacture and therefore inexpensive and which is simple and easy in installation and hence low in cost of application to the rail.

Another object is to produce a device which is efficient after installation in conducting the electric current from rail to rail, of long life and which is not easily removed from the rail either by force applied externally or otherwise.

Still another object of my invention is to produce a rail bond which is adapted to be integrally united to the rail by a heating flame and attaching metal, and by which the ends of the conducting body of the bond is upset or enlarged, thereby presenting an enlarged end area of metal for uniting with the attaching metal.

Another object is to produce a bond which is capable of being installed by such means as to make its attachment to the rail permanently efficient, and avoiding deterioration as in the case of pin expanded, riveted or bolted type of bonds.

These and other new and useful objects as will appear later are secured and attained by the novel construction, combination and arrangement of parts of which my invention is composed and which will appear later as more fully described and claimed and shown in the accompanying drawings in which:

Figure 1 is a side elevation of my bond alone.

Fig. 2 is a side elevation in full of the bond installed on the rail and connecting two adjacent rail ends electrically.

Fig. 3 is an end elevation in part section showing the relation of parts after the bond has been installed. The partial section of the bond is taken on the line 3—3 of Fig. 1. Fig. 3 is taken at right angles to Fig. 2.

Fig. 4 is a top view of one terminal before assembly.

55

Fig. 5 is a section view of the terminal member only of my bond before being assembled on the body portion and.

Fig. 6 is a section view of the same terminal member but taken on the line 3—3 Fig. 1. 60

Fig. 7 is a side elevation view of a bond terminal and body of a modified form of that shown in Fig. 1.

I have found that a bond constructed of a copper cable body composed of a plurality of twisted wires or of a plurality of ribbons and having attached to the ends thereof by means of a mechanical grip, terminals adapted for attaching both the body and the terminal to the rail by welding or brazing, 70 has many desirable points but up to the present time they have been deficient in one point and that is that the contact area between the copper body and the metal by which they are attached to the rail is not sufficient and 75 that unless the terminals are most securely attached to the ends of the copper cable they are liable to be pulled off; therefore, by my new and novel construction I overcome these objections and produce a more efficient bond 80 from these and other standpoints.

In Fig. 1 the flexible body portion is designated by numeral 1 and is usually of copper either wire or ribbon. The terminal members 2 are usually made of steel, iron, nickel 85 or some metallic alloy of these in which they predominate, although other metals may be used, and are of two parts; namely, a shelf 3 and a sleeve 4. Through the sleeve is one 90 or more passages 5 for receiving the body 1 which terminate in an enlarged opening 6.

The terminal member is assembled on the body member by placing the ends of the body through the passages 5 allowing the ends to extend beyond the face of the terminal 95 7 sufficiently to furnish enough metal which compressed will fill the enlarged passage or recess 6.

The terminal sleeve 4 is compressed onto the cable 1 so as to grip it tightly and in the same or an additional operation the protruding ends of the body 1 are compressed back into the recess 6 thereby filling the recess and at the same time extending slightly above the face 7 of the terminal as designated by 8. The upsetting of the ends of

the body 1 forms a head upon the body which rests in the recess 6 and thereby prevents the body from pulling away from the terminal after installation on the rail; in fact tests show that the terminal will come away with the body when the bond is pulled from the rail by means of force applied to the body. The shape of the enlarged passage or recess 6 is not material so long as it is larger than the passage 5 or of such shape that an enlarged head can be formed on the end of the body 1, resting on the passage 5 and recess 6 and preventing the body from pulling away from the terminal.

15 The compressing of the sleeve 4 upon the body 1 and the upsetting of the body ends within the recess 6 may be performed either with the parts cold or hot, the former being preferable where possible, as it is not necessary to secure a weld between the body and terminal to secure the highest efficiency out of my invention, although a welded or brazed union between the two parts would not be found objectionable.

20 Fig. 7 is a modification of my invention in that it covers all the points of advantage shown in the other figures and described herein, but it does not require the terminal to be recessed or depressed, it being necessary only to upset or head over the ends of the body cable 1 forming heads 9 upon the upper face of the terminal.

25 The application of my invention to rails or other conductors to be electrically connected is performed by means well known in the art and for which I make no claims. In Figs. 1 and 2 a bond is shown attached to adjacent rail ends. The bond is first placed in position on the rail and then a 30 heating flame of oxy-acetylene, electric arc or other similar means is applied to the rail surface and bond terminal simultaneously and at the same time a rod or stick of attaching metal is inserted in the flame until 35 the bond terminal and rail are very hot and the attaching metal rod melted and a union is made at that point, then the flame and attaching metal rod are moved to an adjacent point and the process is repeated until 40 the terminal is securely attached to the rail, the attaching means being designated by the numeral 10. This forms an integral union between the bond terminal, the upset body and the rail of highest efficiency and one 45 which is permanent.

50 The use of terminals of iron, steel, nickel or alloys of such metals and which have a higher melting point and test up harder than copper, has peculiar advantages in that 55 the attaching metal 10 which is usually copper, bronze or braze, etc., forms a stronger union with a terminal composed of such metals than with one composed of copper as bond terminals are usually made. A ter-

55 minal so made is cheaper than when made of copper. When made of iron or steel as is usual in my invention the terminal has very little if any scrap value and as it forms a considerable portion of the weight of a complete bond, the incentive to steal the 60 bonds, as is quite general, is practically overcome.

65 Upsetting the ends of the copper body 1 and forming an enlarged mass has been found to possess the advantage of protecting 70 the smaller mass of copper below the upset head from the high temperature of the heating flame in that the mass in the upset copper head tends to receive and absorb the heat, thereby preserving the original good 75 qualities of the copper body.

80 It will be observed from Fig. 4 that the area of the recess or enlarged passage 6 is greater than that of the passages 5 and this is of mutual advantage in that the union 85 between the copper body 1 which entirely fills the enlarged passage 6 and the attaching metal used in installing will be greater than if the ends of the body 1 were not compressed and expanded. This insures an area 90 of contact between the attaching metal and the bond body greater than the cross section area of the metal opposing the body and which is very desirable.

95 The end 8 of the upset body being allowed to extend slightly above the face of the terminal has been found of advantage in that it permits the attaching metal to take a better hold on the copper body than if it were below the face of the terminal or just 100 flush.

Having shown and described my invention, I do not wish to be limited to the exact construction shown and described, as there are variations which can be made and which 105 will be readily recognized by one skilled in the art and which will come within the scope of my invention, but what I do claim and desire to secure by Letters Patent is:—

110 1. A rail bond consisting of a flexible body of copper and terminals of a ferrous metal attached to the ends of the body, the terminals provided with a passage for the body, a recess having a greater cross sectional area than that of the passage, an enlarged head formed up from the ends of the 115 body and located in the recess and extending slightly above the plane of the external opening of the recess.

120 2. A rail bond comprising a body member, ferrous terminal members provided with a passage for the body, a recess in the terminal having a greater cross-sectional area than the passage, an enlarged portion formed up out of the ends of the body and 125 located in the recess and a built-up portion of metal upon the end of the terminal member and body and forming an integral

- union with the enlarged portion of the body and the terminal member and also forming a sloping surface to prevent injury when struck by moving objects; the area of the 5 contacting face of the enlarged portion of the body being greater than the cross-sectional area of the metal in the body.
3. A rail bond consisting of a body member and terminals of a ferrous metal 10 attached to the ends of the body, the terminals provided with a passage for the body, a recess having a greater cross-sectional area than the passage, an enlarged head formed out of the ends of the body and located in 15 the recess and extending slightly above the plane of the external opening of the recess.
4. A rail bond consisting of a body member and terminals attached to the ends of the body, the terminals provided with a passage 20 for the body member and terminating in an enlarged opening, an enlarged head on the body formed out of the ends of the body and located in the enlarged opening and extending slightly above the exterior of the 25 enlarged opening.
5. A rail bond consisting of a body member and terminals attached thereto, each terminal provided with a passage therethrough for the body member and terminating in an enlarged opening, a head formed out of the ends of the body and located in the enlarged opening for receiving molten 30 attaching metal.
6. A rail bond consisting of a body member and terminals attached thereto but formed out of a dissimilar metal, the terminals provided with a passage therethrough for the body member and terminating in an enlarged opening and an enlarged 35 head formed up out of the ends of the body and located in the enlarged opening.
7. A rail bond consisting of a body member composed of a plurality of parts and terminals attached thereto, the terminals 40 provided with a passage therethrough adapted to receive the body and terminating in an enlarged opening and a head formed up out of the ends of the body and located in the enlarged opening.
- 50 8. A rail bond for welding to a rail consisting of a body member and terminals attached thereto, the terminals provided with a passage adapted to receive the body and the outer end of the passage terminating in an enlarged opening adapted to contain an enlarged end of the body.
9. A rail bond terminal consisting of a shelf member and a sleeve member integrally united; a passage therethrough comprising two sections, one section being larger than the other and located in the outer end of the terminal as used.
- 60 10. A rail bond adapted to be welded to a rail comprising a flexible body, an en-

larged head on each end of the body formed up out of the ends of the flexible body, and a terminal surrounding the body end and head and consisting of a sleeve and shelf.

11. A rail bond comprising a plurality of flexible body members, a terminal surrounding the body members adjacent their ends and a portion of the terminal separating the body terminals from each other, and an enlarged head formed up out of the ends of the body members and positioned in the terminal but having one face exposed.

12. A rail bond consisting of a body member and terminals attached thereto, the terminals provided with a passage adapted to receive the body, the passage having two sections one larger than the other, the larger passage containing an enlarged head formed by upsetting the end of the body end one face of the enlarged head being exposed for receiving attaching metal for uniting the bond to a rail.

13. A rail bond adapted to be welded to a rail comprising a flexible body, an enlarged head on each end of the body formed up out of the ends of the flexible body, and a terminal surrounding the body end and head and consisting of a sleeve and shelf.

14. A rail bond adapted to be welded to a rail comprising a body and enlarged head on each end of the body formed by upsetting the ends of the body, a terminal surrounding the body end and head and provided with means for supporting attaching metal in overlapping relation to the enlarged head.

15. The combination with a rail of a rail bond adapted to be welded thereto and consisting of a flexible body of copper and terminals of a ferrous metal attached to the ends of the body, the terminal provided with a passage for the body, terminating in an enlarged recess at the outer end of the bond terminal, an enlarged head formed up out of the end of the flexible body and located in the enlarged recess and, attaching metal united to the face of the enlarged head and to the rail, the area of metal contact between the head and attaching metal being greater than the cross section area of the metal in the body.

16. A rail bond consisting of the combination of a body and terminals, the terminals being made of a metal having a melting point in excess of 1950 degrees Fahrenheit and the body having enlarged upset means formed up out of the extreme ends to prevent separation of the parts and receive molten attaching metal.

17. A rail bond consisting of a flexible body and terminals, the two held together by compression of the terminals onto the body and in addition by enlarged ends formed from the body and engaging with the terminals surrounding the enlarged par-

tion of the body, and means on the said terminals for receiving attaching metal to unite the bond to a rail.

18. The combination with a rail of a rail bond consisting of a body and terminals, an enlarged head on the body preventing separation of the body and terminal, means on the terminal for receiving attaching metal, and attaching metal applied to said means and to the enlarged head for uniting each to the rail.

19. A rail bond adapted to be welded to a rail comprising a body, an enlarged head on each end of the body formed up out of the ends of the body and a shelf surrounding the body end for receiving an attaching metal to unite the body and the shelf each integrally to a rail.

20. A rail bond comprising a flexible body with an enlarged head formed up out of the ends of the body, and surrounded by a terminal composed of a metal having a higher melting point than the bond body and having a portion of the surface of the head exposed for receiving and retaining molten attaching metal.

21. A rail bond for attachment to a rail by welding, comprising a body composed of a plurality of parts and having an enlarged compact head formed up out of the ends of the body and adapted to catch, support and retain attaching metal used in securing the bond to a rail.

22. A rail bond adapted to be positioned on and welded to the side surface of a rail comprising a flexible body member terminating in an enlarged head which is formed up out of the ends of the body, a terminal composed of a metal having a higher melt-

ing point than the body surrounding the bond body and head and attached thereto, the terminal provided with a member projecting therefrom in juxtaposition to the bond head so that attaching metal can be united to both the terminal and head in attaching the bond to the rail.

23. A rail bond comprising a flexible body with an enlarged head formed up out of the ends of the flexible body, a terminal composed of a metal having a higher melting point than the bond body attached to the end of the body and having positioned therein the enlarged head; a portion of the head being exposed for retaining molten attaching metal.

24. A rail bond consisting of a bond body composed of a plurality of members, a head formed up out of the ends of the bond body, the end face of the head having a greater area for contacting with attaching metal than the cross section of the bond body, and a shelf surrounding the sides of these bond heads for receiving attaching metal.

25. The combination with conducting rails of a bond consisting of a body member having an integrally formed enlarged head having a terminal member surrounding the head and body and composed of iron, and attaching metal interposed between the rail and the terminal and head and uniting the head and the terminal each to the rail.

In testimony whereof I affix my signature in the presence of two witnesses.
